Attorney.

UNITED STATES PATENT OFFICE.

MONTGOMERY SLEETH, OF BELLEVUE BOROUGH, PENNSYLVANIA, ASSIGNOR TO FORT
PITT BEDDING COMPANY, OF PITTSBURGH, PENNSYLVANIA.

BED-SPRING.

1,097,885.

Specification of Letters Patent. Patented May 26, 1914.

Application filed May 8, 1913. Serial No. 766,344.

To all whom it may concern:

Be it known that I, MONTGOMERY SLEETH, a citizen of the United States, and a resident of the borough of Bellevue, in the county of Allegheny and State of Pennsylvania, have invented a new and useful Improvement in Bed-Springs; and I do hereby declare the following to be a full, clear, and exact description thereof.

10 My invention relates to bed-springs and has special reference to such springs preferably for use on bed-steeds of a size larger or wider than single beds, such as double-beds, three-quarter beds, etc.

15 The object of my invention is to provide such a bed-spring that will enable one side of the same when in use to maintain a substantially level or horizontal position on its top, or when both sides of the bed are in use.

20 use and by persons of different weights, and a still further object of the invention is to provide such a bed-spring in which the top of the same will be made flexible when in use.

25 To these ends my invention consists, generally stated, in the novel arrangement, construction and combination of parts, as hereinafter more specifically set forth and described and particularly pointed out in the

30 claims.

To enable others skilled in the art to which my invention appertains to construct and use my improved bed-spring, I will describe the same more fully, referring to the

35 accompanying drawing, in which:—

Figure 1 is a plan view of my improved bed-spring showing the folding type in an open position and with the springs removed from one side. Fig. 2 is a side elevation of 40 the same in its closed position. Fig. 3 is a view of one of the rods for connecting the upper ends of the springs together. Fig. 4 is a view of one of the spring rods for connecting the upper ends of the springs. Fig.

45 5 is an enlarged plan view showing the connecting of the upper ends of the springs. Fig. 6 is an end view of a portion of the spring. Fig. 7 is a perspective view of a portion of a spring having a single rigid lower frame.

Like symbols of reference herein indicate like parts in each of the figures of the drawing.

As illustrated in the drawing my invention is shown as applied to a folding bed-

spring *a*, which is composed of the two sections A and B, each of which has a rectangular frame 1 for forming the bottom of the spring, and such sections are connected together at their top portions so as to fold on each other, as hereinafter described. Above each of the lower frames 1 is the rectangular frame 2, which is split or divided longitudinally of the spring and on each frame 1 as at 3, to form the two side frame portions 2' of rectangular shape, and these portions 2' above each of the frames 1 are connected together so as to extend across the spring by the hinges 4.

The frames 1 and 2 are connected together by a plurality of single volute helical springs 5, the lower or smaller ends of such springs being secured to the side and end portions 1' of the lower frames 1 and to bars or slats 6 within and extending across said frames 1, 70 while the opposite or larger ends of such springs are supported within the upper frames 2 by the outer springs being connected in any suitable manner to the side and end portions 2' of the said frames and 75 the intermediate springs being connected to each other and to said outer springs, as hereinafter described.

Extending diagonally between the upper ends of the outer and intermediate springs 85 5 and between the upper ends of such intermediate springs are the spring rods or bars 6, each of which is in the form of a straight helical spring, and is connected to the springs 5 by its ends being bent 90 around said spring ends, while extending between the upper ends of the outer and intermediate springs 5 and between such ends of said intermediate springs are the bars or rods 7, each of which 95 passes through each of said spring bars 6 and is connected by its ends being bent around said spring ends. These spring bars 6 and rods 7 are so connected to their respective springs 5 as to allow the crossing of the 100 bars 6 and rods 7 in their connection with four of such springs, which will thus place the said bars 6 and the said bars 7 in a diagonal position respectively to four of the said springs 5 and in a diagonal position alternately across the bed spring *a*, thereby allowing the springs 5 to remain in line with each other lengthwise and crosswise of the 105 spring.

It will thus be seen that my improved bed-

110

- spring will enable the top of the same, when used, to be flexible at all times by reason of the connections between the springs of the same, and such bed-spring will also enable 5 the spring or resilient connection between the top of the springs to be made in a cheap and rapid manner, without much labor or expense and without the use of complicated parts or clamping connections. It will also 10 be seen that a person using one side of the bed-spring or persons of different weights using both sides of the same each side of such spring will maintain a substantially flat or horizontal position at all times, which 15 will thereby prevent the uncomfortable feeling to such person or persons when the top of the spring is irregular or on the usual incline when in such use, as in ordinary constructions.
- 20 If desired, my invention can be applied to a bed-spring other than the folding or hinged type and different forms of springs and materials can be used in the bed-spring, while various other modifications and 25 changes in the design, application and construction of my improved bed-spring may be resorted to without departing from the spirit of the invention or sacrificing any of its advantages.
- 30 What I claim as my invention and desire to secure by Letters Patent is:—

1. A bed spring comprising a single rigid

lower frame and a plurality of separate upper frames, springs between said upper and lower frames, said upper frames extending longitudinally to form a plurality of separately operative spring sections.

2. A bed spring comprising a lower and an upper frame having a spring portion therein, said lower frame being divided 40 crosswise at its center, and said upper frame being divided crosswise and hinged and divided longitudinally to form a plurality of separately operative spring sections.

3. A spring-structure consisting of a 45 frame, springs supported by said frame, a spring bar diagonally connecting the upper coils of two springs, and a rod diagonally connecting the upper coils of two other springs adjoining said first two springs, said 50 rod crossing said spring bar.

4. A spring-structure consisting of a frame, springs supported by said frame, a helical spring bar diagonally connecting the upper coils of two springs, and a rod diagonally connecting the upper coils of two other springs adjoining said first two springs, said 55 rod crossing the helices of said spring bar.

In testimony whereof, I the said MONTGOMERY SLEETH, have hereunto set my hand. 60

MONTGOMERY SLEETH.
